UNITED STATES PATENT OFFICE.

EDWARD ZAREMBA AND OTTO MANTIUS, OF BUFFALO, NEW YORK, ASSIGNEES TO
ZAREMBA COMPANY, A CORPORATION OF MAINE.

EVAPORATOR.

1,106,532.

Specification of Letters Patent. Patented Aug. 11, 1914.

Application filed August 22, 1912. Serial No. 716,405.

To all whom it may concern:

Be it known that we, EDWARD ZAREMBA, a citizen of the United States, and OTTO MANTIUS, a subject of the Emperor of Germany, both residing at Buffalo, county of Erie, State of New York, have invented new and useful Improvements in Evaporators, of which the following is a specification.

Our present invention relates to the art of evaporating liquids at temperatures higher than atmospheric and at pressures other than atmospheric, more particularly when the liquid is more or less corrosive in character. Heretofore in the case of liquids of this kind it has been necessary to substitute for the cast iron or steel ordinarily used a construction of copper, bronze, lead or some other expensive metal, the choice being determined by its relative corrodibility by the particular liquid to be handled.

In our new system of construction we have provided a method whereby a more or less corrosive liquid can be concentrated in evaporators whose shells, and for the most part, whose steamchests can be made of cast iron or steel. This result is obtained by fitting the cast iron or steel surfaces with an acid-resistant, non-metallic lining, *i. e.*, one of tile, or brick, and cement.

We are aware that linings have heretofore been used for the purpose of protection against corrosive liquids, but in such cases the conditions surrounding the use of these linings have been very different. Generally the lining has been applied to a receptacle or storage tank for acid liquids, a situation in which the temperature and pressure are that of the atmosphere. In the apparatus of the present invention the temperatures are always higher than atmospheric, sometimes as much as 200 degrees higher, while the pressures vary between wide limits running ordinarily from 20 lbs. above atmosphere, down to a vacuum of 27" or 28". The natural effect of the high temperature would be to soften any plastic material that might be used for lining surfaces, and at the same time the use of a pressure other than atmospheric would tend to distort or displace the lining, especially should it become somewhat softened by the temperature. We overcome these difficulties by giving the various cham-

bers of the evaporator such a configuration and making up the lining in such a manner that neither the temperature nor the pressure will have any effect in disturbing the integrity of the lining. 55

It is the object of the present invention to provide a form of evaporator construction as a result of which evaporators for handling acid liquids may be, in large part, built from cheap metals such as cast iron and steel, and in such manner that the acid in the liquid will be unable either to corrode the cast iron or steel, or for the liquid operated upon to be rendered impure as a result of such corrosion. 60

The details of the present invention will be better understood by reference to the following description which is to be taken in conjunction with the accompanying drawing of which— 70

Figure 1 shows a sectional elevation of one evaporator body, and Fig. 2 is a detailed section on the line 2—2. 75

In this case the shell and steamchests of the evaporator body are built of cast iron, consisting of a dished bottom head 1, flanged liquor belt 2, flanged vapor belt 3, dished top head 4. The liquor belt 2 is a plain cylindrical ring from which project at each side, necks 5 and 6; through the opening provided by the walls of these necks pass the tubes making up the heating surface. The top surface of each of these necks is arched, as shown in Fig. 2. To each neck is secured a steamchest casting 9 and 10, also arched at the top, while between each steam-chest and flanged outlet is placed a bronze flueplate 7 and 8, into which the tubes making up the heating surface are secured. This statement completes the description of the evaporator proper together with the steam-chest. The various castings are provided with the necessary outlets such as vapor outlet 11, peephole openings 12, steam inlet 13, liquor outlet 14, condensation outlet 15, air vent 16. 85

The lining that we use for the interior of the evaporator body consists of tile or bricks about 1½" thick, carefully set in any good waterproof cement. The surfaces to which this lining is applied are sufficiently curved in shape to permit us to introduce the tile or 90

bricks used in the lining in the form of arches—an inverted arch 17 in the case of the bottom, and a normal arch 18 in the case of the top and normal arches 19 in the case of the steam chests and necks, and a horizontal arch 20 in the case of the cylindrical walls. By the use of proper workmanship in the placing of the bricks, the arches thus constructed are very strong and can readily resist any pressure that could be imposed upon their exterior as a result of air leakage through the metallic walls or joints of the evaporator body. The tile or bricks used are placed closely together so that should there be any softening of the cementing material as a result of high temperature, it could not have the effect of destroying the integrity of the lining. It is to be noted that in the case of the necks 5 and 6 their bottom 21 and side surfaces, which are not large in extent, can be built flat inasmuch as any pressure that might be imposed at these points could not be sufficient to injure the lining. For this reason we do not limit ourselves to the use of arches at all points of the evaporator body. In the case of the outlets such as the liquor outlet 14, condensation outlet 15 and air vent 16, a brass or copper nipple 23 is screwed into the casting before the lining is put in place. Afterward the lining is built up around these nipples in such a manner as to afford the acid liquor, or any acid vapor produced, no opportunity for attacking the cast iron.

Our specification has been based on the use of a cast iron shell. It is to be understood, however, that we do not limit ourselves to the use of this material, inasmuch as a construction of steel could be substituted without any change in the arrangement of the lining or the efficiency with which it is used.

The heating surface which consists of tubes 24 extending between the plates 7 and 8 may be of copper, brass, lead, steel coated with lead, or any other construction that might be chosen. The flue-plates 7 and 8 can be of copper, bronze, hard lead or any other suitable metal.

Secured to the outer flanges of the steam-chests 9 and 10 are steam-chest covers 25, consisting of cast iron or steel plates lined on the side next to the steam-chest interior with copper 26 or other resistant material.

It would be impracticable to apply the non-metallic lining to these plates inasmuch as they must be removed from time to time—an operation which the brick lining could not long survive.

We have described a single body, which may be used in that form as a single effect evaporator or in conjunction with other similar bodies to form a multiple effect evaporator. In the case of a single effect, live or exhaust steam is fed into the steam-chest

while the vapor produced in the evaporator body passes into a condenser. In the case of a multiple effect, steam is fed into the steam-chest of the first body and the vapor produced passes into the steam-chest of the second body. The vapor produced in the second body passes into the steam-chest of the third body, and so on. It would not be necessary to provide any lining in the steam-chest of a single effect or in the chest of the first body of a multiple effect, for the reason that only steam is present and no corrosive action can occur. In those bodies of a multiple effect following the first body, acid may or may not be present in the vapor, depending on the particular kind of liquid operated upon. Where acids are present the steam-chests would be lined as described.

What we claim as new and desire to secure by Letters Patent of the United States, is:

1. A vacuum evaporator for operating on corrosive liquor at temperatures higher than atmospheric and at pressures lower than atmospheric, said evaporator having a metal shell and having a protective covering therein of masonry arched to withstand external pressure, steam-chests projecting from either side of said shell near its bottom, corrosion-resistant plates for said steam-chests and straight heater tubes of corrosion-resistant metal supported in said plates and traversing the shell of said evaporator to heat the corrosive liquor therein.

2. A metallic vacuum evaporator comprising a vaporizing chamber and a heating surface therein for use in concentrating corrosive liquids as described, said evaporator having its exposed corrodible surfaces lined with material resistant to the corrosive action of the liquid, said lining being arched and self-supporting against pressure on its convex surface and said heating surface comprising acid-resistant pipes passing transversely across the lower part of said chamber and contacting with the corrosive liquid therein to heat the same.

3. In an evaporator the combination of a cast iron or steel chamber having an acid-resistant lining, heating tubes traversing said chamber and supported at their ends in corrosion-resistant flue-plates, steam-chests opposite the ends of said tubes and wear-resistant linings for said chests protecting the walls thereof from corrosive action of acids passing into the chests with the vapor.

4. In an evaporator, the combination of a metal body having projecting necks, a corrosion-resistant plate for each neck to serve as a flue-plate, heating tubes traversing said necks and supported by said plates, steam-chests opposite the ends of said tubes, and an acid-proof masonry covering located next to the interior walls of said body, said covering being arched to render it self-supporting and adapted to withstand pressure upon its

- exterior in case of leakage through said metal body.
5. In an evaporator, the combination of a cast iron or steel body having an acid resistant lining, external steam chests on the lower part of said body and each having a corrosion resistant flueplate, and straight heating tubes of corrosion resistant metal traversing said chamber and supported at their ends in said flueplates.
6. An evaporator for operating on corrosive liquids at temperatures higher than atmospheric and at pressures lower than atmospheric, said evaporator having a tubular metal body positioned on end and having an acid-proof covering where it is exposed to corrosive action of the liquid being concentrated, said covering being arched to resist crushing pressures which might result from leakage through the wall of the evaporator, and acid resistant heater pipes passing transversely across the lower part of said body and contacting with the corrosive liquid therein to heat the same.
- 15 7. In an evaporator, the combination of a metal chamber having a concave bottom and projecting necks, corrosion resisting plates for each neck to serve as a flue-plate, heating tubes traversing said necks and supported by said flue-plates, steam chests opposite the ends of said tubes, and an acid proof covering within said evaporator, said covering being arched over said necks and around the sides of said evaporator to resist crushing strains which might result from leakage through the metal chamber of the evaporator.
- 25 8. In an evaporator for the treatment of corrosive liquids, the combination of a body having a neck near its bottom, a masonry lining for said body and said neck, a flueplate of corrosion resistant metal secured to said neck, heater tubes of corrosion resistant metal carried by said flueplate and contacting with liquid in said evaporator body and a steam chest attached to said neck to deliver a heating fluid to said tubes.
- 35 9. In an evaporator for the treatment of corrosive liquids, an evaporator body lined with masonry, a steam chest for said body having an arched top lined with masonry, a corrosion resistant metal flueplate for said steam chest, heater tubes in said flueplate and a removable cover for said steam chest faced with copper.
- 45 10. In an evaporator for the treatment of corrosive liquors, a metal body lined with masonry and having a neck near its bottom, a steam chest with a removable cover, a corrosion resistant flueplate clamped between said steam chest and its neck and corrosion resistant heater tubes supported by said flueplate and arranged to contact with the corrosive liquid under treatment in said evaporator body.
11. In an evaporator for the treatment of corrosive liquids at temperatures higher than atmospheric and at pressures lower than atmospheric, a metal body lined with masonry and having oppositely disposed necks with arched tops, said tops being lined with masonry, a steam chest secured to each neck, a bronze flueplate clamped between each steam chest and its neck, corrosion resistant heater tubes in said flueplates and a removable cover for each steam chest, said covers being resistant to the corrosive action of the material supplied to said chests.
- 70 12. In an evaporator for the treatment of corrosive liquids at temperatures higher than atmospheric and at pressures lower than atmospheric, the combination of a metal shell having a concave bottom and a dome-shaped top, an acid resistant lining for said shell and its bottom and top, necks projecting from opposite sides of said shell near the bottom and having arched tops protected by a corrosion resistant lining, steam chests secured to said necks and each provided with a corrosion resistant flueplate, straight heater tubes carried by said flueplates and horizontally traversing the lower portion of said shell to heat the corrosive liquid therein and corrosion resisting covers for said steam chests.
- 80 95 13. In an evaporator for the treatment of corrosive liquids at temperatures higher than atmospheric and at pressures lower than atmospheric, the combination of a metal shell having dished top and bottom heads, a masonry lining arched throughout said shell and its heads to withstand external pressure, necks projecting on opposite sides of said shell near the bottom, said necks having arched tops lined with masonry, steam chests secured to said necks and each having an arched top lined with masonry, a corrosion resistant flueplate forming the inner wall of each steam chest, straight corrosion resistant tubes supported by said flueplates and traversing the lower portion of said shell in contact with the corrosive liquid to be evaporated and removable covers for said steam chests.
